UNITED STATES PATENT OFFICE.

FRANK TROUNSTINE, OF NEW YORK, N. Y., ASSIGNOR TO THE NEW YORK WOVEN WIRE MATTRESS COMPANY, OF SAME PLACE.

DESIGN FOR A CORNER-IRON FOR BED-FRAMES.

SPECIFICATION forming part of Design No. 32,886, dated June 26, 1900.

Application filed May 16, 1900. Serial No. 16,934. Term of patent 7 years.

To all whom it may concern:

Be it known that I, FRANK TROUNSTINE, a citizen of the United States, residing in the city, county, and State of New York, have **5** invented and produced a new and original Design for a Corner-Iron for Bed-Frames, of which the following is a specification, reference being had to the accompanying drawings, forming a part hereof, and in which like **10** letters refer to like parts in each figure thereof.

In the said drawings, Figure 1 is a front view of a corner-iron embodying my design. **15** Fig. 2 is a three-quarter back view of the same. Fig. 3 is an under side view of the same.

The rectangular frame A has a lip or flange A', caused by the extension of one of its sides beyond the others, and is provided at one side **20** with a flange B, of triangular shape, con-

nected to the lower edge of the said frame by webs or flanges B'. The lower edge of the front side of the frame is cut upwardly in approximately semicircular form and has a projection C of the same form proceeding therefrom, while at the back the lower edge of the side is provided with a semicircular depending lip E. A horizontal partition D, provided with an aperture D', is located near the bottom of the frame A. **25**

What I claim is—

The design for a corner-iron for bed-frames substantially as herein shown and described.

Signed at the city of New York, in the county and State of New York, this 1st day of **35** May, 1900.

FRANK TROUNSTINE.
